UNITED STATES PATENT OFFICE

2,528,598

LAMINATED ELECTRIC CONDENSER

Albert Liechti, Zurich, Switzerland, assignor to
 Micafil A. G., Zurich-Altstetten, Switzerland,
 a corporation of Switzerland

Application March 24, 1948, Serial No. 16,822
 In Switzerland February 19, 1947

2 Claims. (Cl. 175—41)

1

The present invention relates to electric roll condensers for voltages over about 300 volts, having a dielectric composed of layers of insulating material whereby the thickness of the dielectric is greater at its marginal portions than at its central portion.

The present application is a continuation in part of my copending application Serial No. 7,608, filed Feb. 11, 1948.

It is an object of the present invention to provide a construction of electric condensers in which the dielectric strength of all regions of the dielectric can be fully utilized and glow effects at the edges of the metallic layers are eliminated. This is accomplished by providing more dielectric matter at the border regions of the condenser than at its central region.

It is a further object of the invention to construct the dielectric with thickened border regions in such a way as to avoid harmful deformation of the metallic layers at said regions. According to the invention packages of two or more narrow dielectric layers are placed adjacent to both sides of the edge portions of the metallic laminae. The width of the individual narrow layers forming a package is different and graded to avoid sharp bends of the adjacent foils. The layers are made of oil impregnated material and have the same dielectric constants.

Further and other objects of the present invention will be hereinafter set forth in the accompanying specification and claims and shown in the drawings which, by way of illustration, show what I now consider to be preferred embodiments of my invention.

In the drawings:

Fig. 1 is a transverse sectional perspective view of a condenser strip according to the invention before being coiled and pressed.

Fig. 2 is a diagrammatic transverse sectional view of a modified condenser strip according to the invention.

Fig. 3 is a diagrammatic transverse sectional view of another modification of a condenser strip according to the invention.

Fig. 4 is a diagrammatic transverse sectional view of a further modification of a condenser strip according to the invention.

Fig. 5 is a diagrammatic transverse sectional view of yet another modification of a condenser strip according to the invention.

Fig. 6 is a diagrammatic perspective illustration of a condenser constructed according to the invention and after being coiled and flattened.

Like numerals designate like parts in all figures of the drawings.

2

In the arrangement of foils and dielectric laminae diagrammatically illustrated in Fig. 1 four full width insulating layers 1 are disposed between two metallic laminae 2. At the edges of the latter, packages of two narrow dielectric laminae of different width are placed directly adjacent both sides of the foils and between the foils and the adjacent full width layers. The strip of which Fig. 1 is a cross section, is then wound to form a coil which is compressed and may be flattened to a shape as illustrated in Fig. 6. To obtain the same arrangement of layers after coiling four additional dielectric layers 1' must be provided, for example two below the metallic laminae and two above. In the modification shown in Fig. 1 the widest narrow intermediary layers 3 are directly adjacent the foils 2 and the narrow intermediary layers 4 are placed outside of layers 3.

Fig. 2 illustrates, diagrammatically, an arrangement whereby the packages of intermediary small width dielectric material consist each of three different width layers indicated by dash-dot lines whereby the narrowest layers 5 are directly adjacent the metallic laminae 2 and the widest, 6, are adjacent the full width layers 1, indicated by dash-dot lines.

In the modification diagrammatically shown in Fig. 3 the packages of intermediary layers consist of four different widths and stepwise arranged layers whereby, in one case, the widest, 7, are adjacent one foil 2' and the narrowest, 8, are adjacent the full width layers 1, and in the other case, the narrowest layers 8' are adjacent the other metallic lamina 2'' and the widest, 7', adjacent the full width dielectric layers 1.

The packages shown in any one of Figs. 1 to 3 may be used in an arrangement according to the other figures without departing from the scope of the present invention and the number of narrow layers forming one package may be changed to suit individual conditions.

It is known that the voltage at which a condenser can be operated is proportional to the square root of the thickness of the dielectric; that the power that the condenser can accumulate is the product of tension and current and is proportional to the square of the ionization tension.

Tests have shown that thickening of the border regions relatively to the inner region of a condenser by the factor n permits an increase of the operating voltage by the factor $\sqrt{n}$, provided that the insulating resistance of the dielectric in the central region withstands this increased

voltage. The power of the condenser according to the invention is increased by the factor n .

If the thickened portions of the dielectric are subdivided into halves between two metallic layers 9 by narrow intermediary strips of foil 10 as shown in Fig. 4, as is done in conventional condensers, the permissible operating voltage is increased by the factor $\sqrt{2n}$ and the permissible operating power by the factor $2n$. An increase of thickness of the border regions by, for example, 40% whereby n amounts to 1.4, and insertion of narrow additional metallic linings results in a possible increase of the operating voltage by the factor $\sqrt{2} \times 1.4$ and an increase of power by the factor 2.8.

The narrow additional metallic linings need not consist of independent foils, the metal may be preferably steamed, pressed or sprayed to the respective insulating layers whereby the metal forming a narrow additional coating at both borders of the same dielectric layer may be conductively connected as shown in Fig. 4 whereby homogeneous distribution of electric tension is obtained over the whole mass of the thickened dielectric. In the modification shown in Fig. 4 the metallic laminae 9 project alternately from one side of the dielectric which produces better cooling than the modifications according to Figs. 1 to 3 where the foils are fully embedded in the dielectric.

Fig. 5 illustrates, diagrammatically, an arrangement according to the invention in which both side edges of the metallic layers 2 are wrapped in supplemental dielectric laminae 11, 12, 13 which are folded around the longitudinal edges of the metallic laminae. The innermost laminae 11 is the smallest or narrowest and the width of the laminae increases gradually, 12 being wider than 11, and 13 wider than 12. In this way a gradual thickening of the border regions of the condenser is produced and damage of layers 2 and 1, 1' is avoided when the strip of which Fig. 5 is a transverse section, is compressed.

After a condenser strip which is composed of layers whose relative arrangement may be as shown in Figs. 1, 2, 3, 4, or 5 or equivalents thereof, has been wound to form a coil, the latter is preferably flattened by the application of pressure in such a way that not only the layers of the thickened border regions 14 but also of

the central region 15 are completely closely adjacent one another and a final configuration is obtained as per Fig. 6. The flattened coil, even with much thickened border regions, requires practically no more space than a condenser without thickened border regions though the coil with the thickened border regions can be loaded, electrically, up to four times as much.

While I believe the above described embodiments of my invention to be preferred embodiments, I wish it to be understood that I do not desire to be limited to the exact details of design and construction shown and described, for obvious modifications will occur to a person skilled in the art.

I claim:

1. A high tension electric roll condenser comprising, in combination, relatively thin metallic laminae, relatively thick dielectrics individually composed of a plurality of layers of oil impregnated material and individually disposed between said metallic laminae and having an inner region and border regions, and a small width dielectric placed on each side of said first dielectrics at a border region thereof, said small width dielectric being composed of at least two small width layers of oil impregnated material and having the same dielectric constants.
2. An electric roll condenser as defined in claim 1, said different width insulating layers of each additional dielectric being disposed consecutively according to their widths for obtaining a graduated configuration at the side facing the center of the condenser.
